UNITED STATES PATENT OFFICE.

CORNELIUS BURKE AND WILLIAM E. HARRINGTON, OF LITTLE ROCK, ARKANSAS.

SAFETY ATTACHMENT FOR SWITCH-STANDS.

950,274.

Specification of Letters Patent. Patented Feb. 22, 1910.

Application filed September 24, 1909. Serial No. 519,314.

To all whom it may concern:

Be it known that we, CORNELIUS BURKE and WILLIAM E. HARRINGTON, citizens of the United States, and both residents of 5 Little Rock, in the county of Pulaski and State of Arkansas, have invented a new and Improved Safety Attachment for Switch-Stands, of which the following is a full, clear, and exact description.

10 Among the principal objects which the present invention has in view, are: to provide an attachment for switch stands having various locking stations which will temporarily and permanently render the said locking stations inoperative, thereby rendering it impossible to leave a switch in an open condition unless such is desired; and to provide an attachment having a construction adapted for the purpose above stated and 20 which is durable, effective and simple.

One embodiment of the present invention is disclosed in the accompanying drawings wherein—

Figure 1 is a side elevation of a switch 25 station having attached thereto an attachment constructed in accordance with our invention; Fig. 2 is a horizontal section taken on the line 2—2 of Fig. 1, showing the attachment in conjunction with the switch 30 table of a switch adapted to receive said attachment; Fig. 3 is a fragmentary view in plan showing a portion of a switch table having said attachment in position thereon; Fig. 4 is a vertical section taken on the line 35 4—4 of Fig. 3, of the attachment; Fig. 5 is a vertical section taken on the line 5—5 of Fig. 4 and enlarged therefrom, showing the attachment constructed in accordance with the present invention; and Fig. 6 is a perspective view of the attachment as constructed 40 in accordance with the present invention.

The principal purpose for which our invention is peculiarly designed, is to provide an attachment for the switch stands most 45 generally in use for sidings and other manually operated switches where there is a liability that the switch may be, through neglect, allowed to remain in the open or thrown position. In the form of switch to 50 which we refer the standard or mast is operated by a horizontally extended hand lever which, when the mast is rotated to the proper position, rests above a recess or opening in the edge of a horizontal table. The 55 table is designed to maintain the lever in an extended position excepting when the same

rests over one of the recesses mentioned, which permit the lever to be dropped into the said recess and into a dependent position.

In throwing the ordinary switch in the 60 manner described, the swinging portion of the lever is dropped into one of the recesses above mentioned, which locks the switch in the adjusted position or the position leading into the siding or other junction. Through 65 neglect, this is allowed to remain, and when the oncoming express or passing train traveling on the main track, arrives at the switch it is carried into the siding or junction, causing collision, derailment, or other fatal 70 accident.

The attachment consists in a block 7 adapted in size and shape to fit within the recess A formed in the table B, and extended inwardly from the edge thereof. The upper 75 surface of the block 7 is adapted to remain flush with the surface of the table B, giving thereby, no chance for the lever handle C to be held thereby. The block 7 is provided with an extended pin or dowel 8, and is likewise provided with a spring detent 9. The detent 9 is constructed from flat, spring metal and is secured to the block 7 by means of a bolt 10. The under side of the block 7 is provided with a groove to receive the 85 straight extension of the detent 9, as seen in Figs. 4 and 5 of the drawings. The block 7 is further provided with an extension 11, in the end of which is an eyelet 12 designed to receive the ring 13 of a chain 14. The chain 90 14 is anchored to the eyelet 15 on the switch stand.

The switch stand having the table B is provided with holes 16 bored from the recess A to receive the dowel 8. When the tables 95 B are thus equipped and the stand is provided with one or more blocks 7 secured thereto by the chain 14, the operation is as follows: When it is desired that the switch is to be thrown temporarily, the operator 100 first introduces the block 7 into position on the table B so that the swinging handle C cannot drop into the recess A wherein the switch may be locked in the open or thrown position; in doing so, he inserts the dowel 105 8 within the hole 16, forcing the detent 9 under the structural flange depended from the edge of the table and about the opening of the recess A. The detent 9 is so shaped as to extend under and behind the said depended edge to hold the block 7 firmly in 110 position and to prevent the same from with-

drawing from engagement with the said recess. When it is desired to make this attachment permanent, the table is provided with a hole 17 extended from the top 5 through the said table. A corresponding perforation 18 is formed in the detent 9. When now, the block 7 is placed in position with the dowel 8 extending into the hole 16, the holes 17 and 18 aline to receive a suitable 10 fastening member such as a bolt, rivet, or other usual form of fastening device.

Whether the employment of the block 7 be permanent or temporary, its employment 15 compels the switchman to hold the switch lever C while the engine and train are passing. This is a safeguard against such accidents as are caused by trains running into open switches of sidings, &c., for the reason 20 that the accidents are usually caused by neglect to return the switch to normal position; and therefore, a device of this character, which compels the operator to hold the switch in operative position, removes the element of carelessness or forgetfulness.

Having thus described our invention, we 25 claim as new and desire to secure by Letters Patent:—

1. A safety attachment for switches having a locking table provided with locking 30 recesses in the edge thereof, comprising a block-like member adapted to fill said recesses, and members retaining said block-like member in said recesses.

2. A safety attachment for switches having a locking table provided with recesses 35 in the edge thereof, a block-like member having an engaging extension adapted to hold the said block-like member in position on the said table so that the top of the table and 40 block-like member are flush, and means for holding said block-like member in said recesses.

3. A safety attachment for switches having a locking table provided with locking 45 recesses in the edge thereof, comprising a

block-like member adapted to fit in said recesses so that the top of the said table and block-like member are flush, guides for maintaining the relative positions of said block-like member and said table, and means for 50 fastening the said block-like member in said recesses.

4. A safety attachment for switches having a locking table provided with locking recesses in the edge thereof, comprising a 55 block-like member having an extension provided with an eyelet to receive a fastening chain, a fastening chain for said block-like member anchored to the stand of said switch, a dowel extended from said block-like member to fit a hole provided in said table for the support of said block, and a resilient detent adapted to snap over a structural ridge in said table to hold the said block in operative position in said recess. 60

5. A safety attachment for switch stands having a locking table provided with locking recesses in the edge thereof and a perforation adjacent thereto, comprising a block having an extension provided with an eye to 70 receive a chain, a chain attached to said extension and anchored upon the switch stand, a pin extended from the end of said block and adapted to fit within a hole provided in said table, a detent secured to said block 75 and adapted to extend under said table and provided in its free end with a perforation arranged to aline with the said perforation in said table said perforation being arranged to receive and hold a fastening device for 80 holding the block in position in said recess.

In testimony whereof we have signed our names to this specification in the presence of two subscribing witnesses.

CORNELIUS BURKE.
WILLIAM E. HARRINGTON.
